By his Attorney Geo. W. Beeler

J. M. Alter Inventor

UNITED STATES PATENT OFFICE.

JULIUS M. ALTER, OF BROOKLYN, NEW YORK.

LOOSE-LEAF ALBUM.

Application filed January 18, 1923. Serial No. 613,444.

To all whom it may concern:

Be it known that I, JULIUS M. ALTER, a citizen of Russia, residing at New York city, borough of Brooklyn, in the county of 5 Kings and State of New York, have invented certain new and useful Improvements in Loose-Leaf Albums, of which the following is a specification.

This invention relates to the construction 10 of loose leaf binders or books, which though adapted for general business uses are designed especially for the holding of talking machine record disks.

Among the objects of the invention is to 15 improve the construction of an album of the character indicated with respect to the simplification of the back, making a cheaper and stronger construction than has heretofore been made.

Another object of the invention is to improve the hinge construction both as to simplification of design and material and also as to durability.

A still further object is to improve the construction of the leaves or envelopes and the manner of securing them detachably in the back of the book.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a general perspective view indicating my improved album laid open.

Fig. 2 is a detail view of the metal piece of the back and the flexible hinges secured thereto ready for assemblage.

Fig. 3 is a sectional detail of the back and especially indicating the construction and operation of the pins.

Fig. 4 is a detail view indicating the construction of the hinge portion of the envelope.

Referring now more specifically to the drawings I show my improvement as being embodied in an album having a back 10, two stiff or board covers 11, and a series of leaves indicated herein as consisting of envelopes 12 for holding record disks.

The principal feature of novelty of the back 10 is a metal piece 10^a made preferably from a single strip of sheet metal whose edges 13 are each bent upon itself at 14, the extreme edge portion 15 of which lies substantially flat adjacent to the outer surface of the next adjacent strip 16. The two edge portions 13 lie in substantially parallel planes and embrace between them the hinge portions 12' of the envelopes. The main 65 middle portion of the metal channel member 10^a is rounded as usual and is reinforced by any suitable number and arrangement of transverse grooves 17 formed therein. The two edge portions 13 furthermore are 70 punched with aligned holes 18, there being preferably three pairs of such holes for a like number of fasteners for the leaves or envelopes.

The hinges, constituting another important feature of novelty of this construction, comprise relatively narrow strips of tough flexible material 19, one edge of each being inserted between the portions 15 and 16 of each edge 13 and there securely fastened by 80 any suitable means including the crimping of such edge portions firmly together and by the formation of transverse creases or grooves in any suitable number or arrangement as indicated at 20 formed directly 85 in or through the two cooperating parts of the edge of the back. The opposite edge portion of each hinge is fastened to the adjacent cover 11 in any usual or approved manner, a finishing strip of paper or the like being applied thereover as shown at 21. The back is provided with a finishing strip 10^b cemented as at 10^c on the outside surface of the metal strip 10^a.

Each envelope 12 has a closed bottom 22 95 while the hinge portion 12' thereof is made up of three plies 23, 24, and 25, all secured rigidly together and through which are formed a suitable number of holes preferably reinforced with eyelets 26. The envelope for flexibility is preferably scored at 27 coincident with the folding and formation of the hinge portion.

Various fastening means may be employed for securing the envelopes to the back, but for this purpose I show and prefer to use a series of pins 28 each consisting of a tight coil of wire the length of which coincides with the space between the edge portions 13 of the back and along which the eyelets 26 110

of the envelopes are adapted to slide. For securing the pins in place a pair of short screws 29 are employed, the same being passed inward through the holes 18 formed 5 in the back flanges 13, the heads of the screws lying flatly against the outer portions 15 of said flanges while the threaded portions of the screws are designed to mate directly with the inner surface of the ends 10 of the pin coil. Thus the ends of the pins are fixed firmly and rigidly in place in the flanges of the back but the middle or main portion of each pin 28 is free to flex outward as suggested in dotted lines 28' in 15 Fig. 3 when the book is open. This construction is not only cheap but exceedingly neat and strong, adapting the construction well for practical purposes as well as attractive appearance.

20 I claim:

1. The herein described book construction

comprising a channel-shaped metal back having spaced parallel edges, a series of leaves having hinge portions located between said edge portions of the back, a pair 25 of flexible hinge strips having their edges secured to said edge portions of the back, and fasteners for the leaves passing through said hinge strips, the metal back edges, and the leaves.

2. In a book construction, the combination of a back member of channel form made of rigid sheet material and having edge portions each folded upon itself, and a pair of flexible hinge strips having their edges 35 gripped between the folded portions of the respective edges of the back, said back edges being crimped for locking the hinge portions.

In testimony whereof I affix my signature.

JULIUS M. ALTER.
